(57) **CLAIM**

The ornamental design for a rehabilitation training apparatus, as shown and described.

DESCRIPTION

FIG. 1 is a front perspective view of a rehabilitation training apparatus showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and,

FIG. 9 is a reference view showing use state thereof.

The broken lines in FIG. 9 are for illustrative purposes only and form no part of the claimed design.

1 Claim, 9 Drawing Sheets(56)
